ART OF REFINING EDIBLE OILS, FATS AND ANALOGOUS PRODUCTS

Vaman R. Kokatnur and Oliver S. Plantinga, New York, N. Y., assignors to Autoxygen Inc., New York, N. Y., a corporation of New York

No Drawing. Application June 20, 1935, Serial No. 27,608. Renewed November 22, 1937

16 Claims. (Cl. 87—12)

Our present invention is concerned with improvements in refined edible oils, fats and generally analogous materials such as waxes and rosins and with improved processes by which such products are produced.

An object of the invention is to provide improved edible products typical examples of which are refined corn oil, cotton seed oil, linseed oil, castor oil, tallow, lard, cocoanut oil, etc., so refined and purified that their spoilage or rancidity due to bacterial or mould attack is positively inhibited over much longer periods of time than has heretofore been considered possible. In fact the refined products will apparently keep indefinitely.

Another object is to provide a greatly simplified and cheapened and more expeditious process of refining such materials.

Another object is to provide a highly efficient process by which the loss in the refining operation of valuable oil or other desirable end products is greatly reduced in comparison with prior processes.

Another object is to provide a process in which the foots constitute a valuable by-product convertible into active refining agents for re-use in refining subsequent batches of the same material from which the foots were derived.

Heretofore refining processes for materials of the types here involved have concerned themselves with one or more of the following distinct refining steps: (1) removal of free acids, (2) bleaching, (3) removal of mucilaginous and other deleterious materials, and (4) rendering the final product tasteless and odorless.

The practice of bleaching has been carried out more to satisfy a popular misconception as to the impurity of colored oils than because of any sound reasons which can be advanced for increased nutritional, therapeutic or other valuable properties of the bleached product.

In fact modern bleaching processes involving violent chemical reactions such as pyrogenic decomposition not only result in a substantial loss of refined end product but seriously impair or destroy the vitamin content thereof. Similar waste of end products and increase in worthless foots have resulted from prior acid removal methods and prior methods of separating out the mucilaginous constituents of crude oils.

It has previously been proposed to use organic peroxides as bleaching agents but as evidenced by the Ludecke Patent No. 901,718 and by the patent to Kokatnur et al., No. 1,883,707, such peroxides have always been reacted with the oils at

temperatures in excess of 100° C. at which temperatures pyrogenic decomposition occurs and considerable conversion of otherwise valuable oil into worthless foots results. Such prior processes have likewise involved the use of alkali earths both as pyro-oxygen decomposition agents and to neutralize the free fatty acids present. Such alkalis have heretofore been used in excess of the amount required to effect such neutralization. An objection to the use of this type of alkali is that the alkali earth soaps resulting from the reaction are soluble in the oils and are difficult to eliminate from the end product.

The patent to Kokatnur above identified suggests that the process which it discloses helps to inhibit rancidity and tends to render the oil tasteless and odorless. However that patent teaches no reliable method of accomplishing such results and their sporadic and partial accomplishment by the patented process was entirely accidental and fortuitous and could not be duplicated because the critical factors determinative of such results were not known or even surmised.

We have discovered that there are two controlling factors involved in producing these results, one is the use of peroxides in excess of that required for decolorizing and in sufficient quantity so that the final product still contains a substantial amount of peroxide. We have likewise discovered that by carrying out the process at temperatures in the order of 50° to 60° C., that is at temperatures below the temperatures of pyrogenic decomposition of the peroxides, bleaching may be substantially inhibited although some decolorization does occur. The chemical reaction which takes place is mild as compared to prior processes involving the use of organic peroxides. The amount of end product is increased and from the foots of the process we are able to produce organic peroxides from natural constituents of the oil which are suitable for treating subsequent batches of the oil.

We have found that deodorization and rancidity can be inhibited indefinitely if sufficient peroxide is used so that the end product still carries peroxide. This is in direct contra-distinction to prior methods involving temperatures high enough to effect pyrogenic decomposition of the peroxides and while the following explanation is merely tentative, experiments would seem to bear it out. Whereas heretofore practically all of the peroxide has been decomposed and spent in the violent chemical reaction which causes bleaching, the peroxide has little effect on the other phases of refining. Where however

by our process the bleaching action is slight and an excess of peroxide is used, the other phases of the refining process are more effectively accomplished. It would also explain why when 5 the peroxide spends itself substantially in the bleaching action of the prior process, no material deodorization or rancidity prevention takes place since there is little or no peroxide left for selective action in other phases of refining. 10 Furthermore our process definitely facilitates the removal of mucilaginous and other deleterious ingredients from the crude oil, although whether this is due entirely to the use of an excess of peroxide and the lower temperature, or 15 due to the different type and amount of alkali used, or due in part to all of these factors is difficult to determine.

In our present process we preferably use alkali metal hydroxides, carbonates or weak acid salts 20 as opposed to alkali earth hydroxides such as those of calcium, barium, strontium and magnesium. This improvement in the process prevents the formation of alkali earth soaps which are soluble in oils and contaminate the final oil 25 product and causes the formation of soaps insoluble in oil. As a result the soap produced from the free fatty acids by our process, settles out along with mucilaginous and deleterious matter thrown out of the solution or emulsion 30 by the organic peroxides. The fact that the foots in our process carry substantially all of the mucilaginous matter and smaller amounts of the neutral oil than they have carried heretofore, indicates that the emulsifying property of gums, 35 rosins and soap has been broken down or reduced by the peroxide.

Where in accordance with the preferred embodiment of the invention we use a peroxide of one or more of the natural ingredients of the 40 crude oil, such peroxides can be derived from the foots. In corn oil refining for instance we use the peroxides of the total corn oil fatty acids and the foots from such refining process are essentially composed of such fatty acids. Such 45 corn oil peroxides can be made from the foots at a cost approximating 25 to 50 cents per pound as opposed to the commercially available benzoyl peroxide which costs approximately 4 to 8 times as much. Similarly, peroxides of cotton seed 50 oil, cocoanut oil, linseed oil etc. prepared from the foots may be used to refine the respective oils.

The fact that in our process peroxides act as 55 anti-oxidants rather than as pro-oxidants and inhibit rather than promote rancidity, is directly contrary to the teachings of the prior art. That the action of the peroxides continues long after the heat treatment has occurred is evidenced by the fact that deodorization in many cases requires several weeks and occurs in storage. Such 60 deodorization of course may be effected more rapidly if desired by blowing superheated steam through the oil while the latter is under vacuum. Even when this is resorted to however, oils which 65 normally take ten to twelve hours of steam blowing can be completely deodorized in approximately $\frac{1}{4}$ to $\frac{1}{2}$ of that time.

The invention may be more fully understood 70 from the following typical examples of methods for treating certain oils, fats and waxes.

Example I—Corn oil refining

A thousand parts of crude corn oil containing approximately 2.85% free acids are treated with 75 5 to 10 parts of pure peroxides made from corn

oil foots at a temperature of 50 to 55° C. with constant agitation for about an hour. To this a solution of caustic soda of 16-40 Bé. containing 4.25 parts is then added and the whole agitated again for another hour or two. The foots and mucilaginous matter are allowed to settle for a few hours after which time the foots are separated from the clear neutral oil either in a filter press or by decanting or by any other suitable manner. If desired, the caustic soda solution and peroxides may be introduced into the crude oil together, in which event careful control particularly of temperature is essential less the oil be bleached too much. A minor amount of bleaching always takes place in neutralization whether the peroxide is present or not. While the presence of alkali enhances bleaching, it tends to make other phases of the refining process more inefficient. Therefore, if the alkali is added at the beginning of the process the 20 neutral oil should be separated from the foots as soon as the desired color is obtained. The foots are distinctly superior to those obtained from prior processes being of better color consistency and odor and containing less neutral oil. 25 The refined neutral oil so obtained is between 95 and 96% of the crude in contradistinction to prior methods where not more than 92 to 93% of refined oil is obtained from the crude.

Variations of Example I

While the above example deals with a preferred procedure, it will be apparent to those skilled in the art that many variations thereof might be made without departing from the spirit of the 35 invention. For instance instead of using caustic soda, other alkali metal hydroxides may be used. Sodium carbonate, borate or phosphate, with or without the addition of bicarbonate, boric acid, or phosphoric acid to reduce their pH may be used 40 to neutralize the free acid or bring down and precipitate the mucilaginous matter or both. Neutral solids such as aluminum sulphate or common absorbents such as fuller's earth, and certain acids like sulphuric, nitric and phosphoric 45 in high dilutions may also be used to precipitate the mucilaginous matter. Of course this treatment will not neutralize the free acids, if present. It would merely bring down the mucilaginous matter in the presence of organic peroxide. From 50 the standpoint of refining, however, this is more important than neutralization and must be done thoroughly. Particularly good results are obtained in cocoanut oil, cotton seed oil, olive oil and soy bean oil by this process. However almost any oils, fats and waxes may be refined by this process with advantage. Most oils and fats contain in their crude unrefined state 1 to 10% of free acids. Palm oil and many waxes contain free acids in a much higher percentage namely 60 as high as 50 to 60% and in such cases neutralization should not be resorted to at all in refining. The materials which contain such high percentages of free acids should be treated with neutral salts or acids as precipitant for foreign materials, 65 since neutralization processes would result in the loss of too much product. In the treatment of waxes, free acids are part and parcel of the wax and there would be no good purpose served in throwing the free acids away. The oil refined by 70 our process is in most instances characterized by a lower viscosity than similar oil refined by prior methods. This for many purposes is helpful due to the more ready flowability of the oil. Lower viscosity also seems to have a direct relation to 75

the prolonged induction period for oxidation which characterizes oil refined by our process.

Example II—Preserving lard

5 To a thousand parts of refined edible lard dissolve $\frac{1}{16}$ to $\frac{1}{8}$ of a part of organic peroxide made from edible oil or fat with or without the aid of heat. The treated material may or may not contain any free acids since the acids do not interfere with the action of the peroxides to inhibit or prevent rancidity. In cases where the material is colored as in the case of cows butter and where it is undesirable to bleach it, a lower limit of peroxide should be used. A negligible amount of free acid would help to slow up the bleaching action. The product so produced is insured against rancidity for long periods of time and tests indicate that biscuits or other bakery products made with such preserved oils or fats also seem to show a far longer life than products made with ordinary oil or fats.

Having thus described our invention, what we claim as new and desire to secure by Letters Patent is:—

25 1. A process of refining oils, fats or waxes, which includes the steps of reacting material to be treated with organic peroxide at a temperature substantially less than 100° C. and in the presence of a precipitant for mucilaginous material said material and said precipitant being of the type for which the peroxide acts as a catalyst in facilitating precipitation.

2. A process of refining raw non-mineral oils, which includes the steps of reacting oil with organic peroxide at a temperature well below the pyrogenic decomposition temperature of said peroxide and in the presence of a precipitant which neutralizes free acids without producing soaps soluble in the material being treated.

40 3. A process of refining oils, fats or waxes, which includes the steps of reacting material to be treated with organic peroxide derived from the foots of the refining process at a temperature well below the pyrogenic decomposition temperature of said peroxide and in the presence of a precipitant for mucilaginous material which neutralizes free acids without producing soaps soluble in the material being treated and separating the foots from the desired end product.

50 4. A process of refining oils, fats or waxes, which includes the steps of reacting material to be treated with organic peroxide at a temperature well below the pyrogenic decomposition temperature of said peroxide and in the presence of a precipitant for mucilaginous material, a sufficient amount of peroxide being introduced into the material being treated to insure the presence of peroxide in the end product.

5. A process of refining oils, fats or waxes, which includes the steps of reacting material to be treated with organic peroxide at a temperature well below the pyrogenic decomposition temperature of said peroxide and in the presence of a precipitant for mucilaginous material which neutralizes free acids without producing soaps soluble in the material being treated, a sufficient amount of peroxide being introduced into the material being treated to insure the presence of peroxide in the end product.

70 6. A process of refining oils, fats or waxes, which includes the steps of reacting material to be treated with organic peroxide at a temperature

well below the pyrogenic decomposition temperature of said peroxide and in the presence of a precipitant for mucilaginous material which neutralizes free acids without producing soaps soluble in material being treated and separating the foots from the desired end product, a sufficient amount of peroxide being introduced into the material being treated to insure the presence of peroxide in the end product.

7. A process of refining edible oils and fats which includes the steps of reacting material to be treated with organic peroxide at a temperature in the order of 50 to 60° C. and in the presence of a precipitant for mucilaginous material.

8. A process of refining edible oils and fats which includes the steps of reacting material to be treated with organic peroxide at a temperature in the order of 50 to 60° C. and in the presence of an alkaline precipitant for mucilaginous material, which precipitant is of the type capable of neutralizing free acids without the production of soaps soluble in the desired end product.

9. A process of refining edible oils and fats which includes the steps of reacting material to be treated with organic peroxide derived from the foots of the refining process and at a temperature in the order of 50 to 60° C. and in the presence of a precipitant for mucilaginous material of the type capable of neutralizing free acids without the production of soaps soluble in the desired end product and separating the foots from the end product.

10. A process of refining corn oil, said refining process including reacting peroxide with the oil at a temperature well below pyrogenic decomposition temperature of the peroxide, said process also including the introduction of an agent serving as a precipitant for mucilaginous material and a neutralizer of free acids.

11. A process as set forth in claim 9 wherein the peroxides are formed from the foots separated out during the refining process.

12. A method as set forth in claim 10 wherein peroxides of corn oil fatty acids are used.

13. A method of refining vegetable oils which includes the steps of adding an organic peroxide with crude oil and reacting the peroxide with the oil in non-violent fashion and at a temperature below the pyrogenic decomposition temperature of the peroxide whereby to effect partial bleaching and adding to the material being treated, an alkali for neutralizing free acids without the formation of oil-soluble soaps.

14. A process of refining edible oils or fats which includes simultaneously reacting the material to be treated with organic peroxide at a temperature in the order of 50 to 60° C. and neutralizing free acids with an alkali metal hydroxide.

15. A process of refining edible oils or fats which includes simultaneously reacting the material to be treated with organic peroxide at a temperature in the order of 50 to 60° C. and neutralizing the free acids with a weak acid salt.

16. A process of refining edible oils or fats which includes simultaneously reacting the material to be treated with organic peroxide at a temperature in the order of 50 to 60° C. and neutralizing the free acids with a carbonate.
